HOUSEHOLD MIXER

Walter E. Moore, Belnior, Mo., assignor to Knapp-Monarch Company, St. Louis, Mo., a corporation of Delaware

Original application May 10, 1954, Serial No. 30,391.
Divided and this application August 2, 1954, Serial No. 31,706

Term of patent 14 years

(Cl. D44—1)

Figure 1 is a side elevational view of a household mixer embodying my new design;

Figure 2 is a perspective view of the mixer shown in Figure 1; and

Figure 3 is an end view of the housing end cap shown at the right-hand ends of Figures 1 and 2.

The side of the mixer opposite that shown in Figure 1 of the drawing is substantially identical except for the omission of the circular recess shown at the forward lower end of the motor.

The essential features of my design reside in the portions shown in full lines.

This case is a division of my copending application Serial No. D. 30,391, filed May 10, 1954, and entitled "Liquidizer."

I claim:

The ornamental design for a household mixer, substantially as shown and described.
